WILLIAM M. DUNCAN, OF ALTON, ILLINOIS

METHOD OF CASTING WHEELS AND OTHER ARTICLES

Application filed June 22, 1931. Serial No. 545,970.

This invention relates to certain new and useful improvements in method of casting wheels and other articles, the peculiarities of which will be hereinafter fully described and claimed.

This application is a continuation in part of my prior application on improvements in cast wheels, Serial No. 506,699, filed January 5, 1931.

The main objects of my invention are first, to form a homogeneous outer surface of a circular, cylindrical or other shape of casting; second, to protect a chilled surface on such a casting from the heat of spokes or other integral connections between adjacent portions of said article so as to obtain a chilled surface that is homogeneous and without soft spots; third, to provide inner and outer walls for one of said portions so that the heat of said integral connections from the inner wall to the other portion of the casting is kept from affecting the chilled surface of the outer wall; fourth, to shield the chilled surface of one wall from the heat of the other wall; fifth, to provide for the escape of gases through the inner wall and maintain the outer wall in solid homogeneous condition; sixth, to lessen the shrinkage strains on said integral connections; seventh, to retard the withdrawal of heat from an inner wall and its integral connections to an adjacent portion opposite an outer wall, and thereby retain the necessary heat for proper annealing of the casting in the soaking pit; and eighth, to develop the full strength of the spokes or other integral connections.

In the accompanying drawings in which like reference numerals indicate corresponding parts,

Fig. 1 represents a plan view of a wheel embodying my invention, the upper half being a face view and the lower half being a sectional plan through the tread to show the construction, and indicating the application of a chill and a sand mold; and

Fig. 2, a cross section of Fig. 1 on the line A—B.

Ordinarily, that section of the rim of a wheel, gear or other article having spokes that is radially out from a spoke integral therewith, will not chill at all,—or at least not to the depth of chill at other parts of the rim, due to the additional body of metal in the spoke. Also the shrinkage of the solid spoke connecting the rim and hub tends to cause a depression in the rim if thin, or subject it to internal shrinkage strains if it be thick, when the cast iron or other metal cools.

In my construction however, the rim of the wheel and gear, and the cylinder of the roller, is of double wall construction. The outer wall is preferably subjected to the action of a chill, and the inner wall is integral with solid spokes connecting it to the hub. The outer wall is continuous and the inner wall is parallel to it but provided with openings where the dry sand core forming the interposed chamber needs support. These openings also vent the gases formed between these walls.

Referring to the drawings, the numeral 1 designates a hub having radiating spokes 2, preferably solid and integrally connecting said hub with the hollow rim constituting a one-piece casting of cast iron or other suitable metal.

This rim comprises an outer wall 3 and an inner wall 4 spaced therefrom and preferably parallel to the outer wall and connected by front and rear face walls forming an interposed chamber preferably extending completely around the rim. Said outer wall 3 is practically uniform in section and separated by the interposed chamber from the solid spokes 2 that are integral at their outer ends with said inner wall 4.

A series of spaced rectangular or other shaped openings 5 are formed in said inner wall preferably about a third of the depth of said inner wall. These openings divide the in-

ner wall into partial segments 6 as shown in the figures. They also serve to support radial inward projections from a dry sand core 8 having an outer circular portion 9 adapted to space apart the said walls and form the interposed chamber. These openings also allow of releasing the gases that may evolve from said circular portion 9 within the rim. This dry sand core forms the peripheral portion 10 of a green sand mold 10 in which are formed the spokes and the hub. The hub has a dry sand core for the usual or any desired bore.

Surrounding the rim is a metal chill 11, Fig. 2, of uniform thickness adapted to exert a uniform chilling effect upon the substantially uniform thickness of the outer wall of my hollow rim, so that a uniform homogeneous chilling effect is produced on the outer surface of the outer wall. Since the solid spokes 20 are connected to the inner wall and the interposed chamber separates the inner wall from the outer wall as shown, the heat from said spokes has practically no effect upon the outer wall as would be the case if the spokes 25 were directly connected thereto. Furthermore, the dry sand core forming said chamber serves to retard the withdrawal of heat by the chill from the inner wall, and thus shields the inner wall. More heat is thus retained in 30 the spokes and hub, which heat is vital for proper annealing in the soaking pit. Strains are more perfectly removed and less liability of fracture of the spokes is obtained.

Between the outer and inner walls I provide bridge connections of cylindrical or other form 13 integrally connecting and bracing the two walls. These bridge connections are shown opposite the partial segments alternating with the segments at the ends of 40 the spokes, so that the segments at the ends of the spokes are not directly connected to the outer wall except by the front and back walls of the rim. These bridge connections may be otherwise spaced if desired.

45 Thus it will be seen that the ends of the solid spokes and the partial segments of the inner wall to which they are integrally connected are practically heat insulated from the outer chilled wall and have practically no extra heating effect upon the outer wall and consequent formation of soft spots, which is the case in the usual construction. Therefore the chill may be of uniform cross 50 section, instead of having the irregular enlargement of cross section used in the endeavor to compensate for the extra heat at different portions of the tread opposite the spokes; furthermore, by my method more heat 55 is retained in the spokes and the hub and the metal of the spokes is less subject to internal strains and consequent fracture. These spokes can thus be made of sufficient size to provide the strength required in rough 60 usage.

I claim:

The method of casting a circular article having a double walled hollow rim integrally connected by spokes to a hub, in a sand mold, consisting of chilling the outer wall of said rim, shielding the inner wall opposite the ends of the spokes from the said chilling action so as to retard the loss of heat therefrom and to prevent strains and fractures while the article is cooling.

In testimony whereof I have affixed my signature.

WILLIAM M. DUNCAN.
